CLAIM

The ornamental design for laces on a shoe, as shown and described.

DESCRIPTION

FIG. 1 is a perspective view of laces on a shoe showing my new design.

FIG. 2 is a left side view thereof;

FIG. 3 is a right side view thereof;

FIG. 4 is a top plan view thereof;

FIG. 5 is a bottom plan view thereof;

FIG. 6 is a rear elevation view thereof; and,

FIG. 7 is a front elevation view thereof.

The broken lines shown in the drawings represent portions of the shoe that form no part of the claimed design.
